BLAST FEED STOKER

Paul A. Ketchpel, West Englewood, N. J., assignor,
by mesne assignments, to The Standard Stoker
Company, Inc., (1922), a corporation of Dela-
ware

Application April 22, 1933, Serial No. 667,356
Renewed April 20, 1938

5 Claims. (Cl. 110—104)

My invention which relates to blast feed stokers for locomotive or similar boilers has for its principal object the provision of a stoker of the type specified wherein a pressure fluid blast propels the fuel through a delivery conduit in communication with the firebox, the fuel being propelled through the delivery conduit in a manner so that the bulk of fuel is discharged from the conduit along the top wall thereof and a portion of this fuel is deflected laterally by an abutment which crosses the stratum of fuel.

It is also an object of this invention to provide in a stoker of the blast feed type, a fuel discharge conduit consisting of a substantially horizontal fuel receiving portion, a horizontal fuel discharge portion above the plane of said receiving portion and in advance thereof, and a feed section connecting said portions, the fuel discharge conduit being of a shape and configuration such that the fuel is passed therethrough without any undue friction which would otherwise reduce its velocity.

A still further object of the present invention resides in the provision of a blast feed stoker for locomotives in which a trough is mounted rigidly on the tender beneath the fuel bin, the fuel discharge conduit is mounted on the locomotive and an intermediate conduit section is disposed between the trough and the discharge conduit, the intermediate section, comprising a plurality of flexibly jointed elements which afford lateral and vertical displacement of the intermediate section, the longitudinal movement between the locomotive and tender being compensated by telescoping the rearward end of the intermediate section with the forward end of said trough.

Another object of this invention consists in the method and means of introducing cinders and other partly consumed products of combustion into the stream of coal as it is propelled through the stoker whereby the partly consumed cinders, while in a hot state, are thoroughly mixed with the coal and thus projected into the firebox and upon the grate thereof, which has the effect of promoting combustion.

More specific objects and advantages will be apparent as the description of the invention is read in connection with the accompanying drawings, in which

Figure 1 is a central vertical longitudinal section of the improved blast feed stoker, showing its application to a locomotive and its tender;

Figure 2 is a partial view of the stoker as seen from within the locomotive firebox;

Figure 3 is a sectional view taken on the line 3—3 of Figure 2;

Figure 4 is a view taken on the irregular line 4—4 of Figure 1;

Figures 5, 6, 7 and 8 are cross sections of the stoker discharge conduit taken on the corresponding lines of Figure 1;

Figure 9 is a transverse section taken on the line 9—9 of Figure 1;

Figure 10 is a view partly in elevation and partly in section showing a modified form of the invention illustrated in Figure 1;

Figure 11 is a central vertical longitudinal section of the locomotive tender showing a portion of the stoker illustrated in Figure 10 in section; and

Figure 12 is a detailed longitudinal section of the front end of the locomotive, showing the smokebox and a portion of the cinder return tube.

In Figures 1 to 9 inclusive, which illustrate one form of this invention, the locomotive A is provided with a firebox 10 having a rear wall 11 which is provided with a firing opening 12 disposed above the grates 9. The tender B is connected to the locomotive A by a coupler C and includes the floor 13 above which is disposed a coal bin 14. The floor 13 is apertured as at 15 and slideable plates 16 cover this aperture entirely or they may be moved to partially uncover the aperture so that coal may drop into the trough 17. This trough or transfer conduit preferably, is rigidly mounted beneath the floor 13 and houses a conveyor screw 18 which urges the fuel forwardly toward the firebox for propulsion thereinto as will presently appear. The motive power for operating the conveyor screw 18 is generated by a prime mover such as 19 and is transmitted to the conveyor screw by the gearing 20 at the rear of the trough 17.

The forward end of the trough 17 terminates in a tubular extension 21 and the conveyor screw 18 may protrude into this extension for a short distance. A pressure fluid head 22 is positioned in the tubular extension 21 immediately forward of the conveyor screw 18 and discharges a relatively powerful fan-shaped blast of pressure fluid for propelling coal forwardly into the firebox through the intermediate conduit 23 and the discharge conduit 24.

This discharge conduit 24 consists of a forwardly directed approximately horizontal portion 25 which passes through the lower portion of the firing opening 12, a downwardly and rearwardly extending section 26 which terminates at a point below the cab deck 27 in a rearwardly and horizontally extending fuel receiving portion 28. Secured in any suitable manner to this portion 28, as by the bolts 29, is an end member 30 of the intermediate conduit 23. A plurality of such members are utilized to form the intermediate conduit and they are joined together by pintles such as 31 and have their coacting surfaces of a form which permits relative angular movement between them. At its end remote from the discharge conduit 24, the intermediate conduit 23 is secured to a sleeve 32 which fits freely over the tubular extension 21 and telescopes thereover when the locomotive and tender are negotiating curves. If desired, a bar such as 33

may be used to prevent sagging of the intermediate conduit 23. This bar is loosely attached between the discharge conduit 24 and the sleeve 32 in a manner which will permit a slight angular displacement of the intermediate conduit 23 when the locomotive and tender are passing over switches, frogs or turntables.

The discharge conduit 24 is of novel construction and permits coal to be passed therethrough in an efficient manner. At its rearmost end, the horizontal portion 28 of the discharge conduit is circular in cross section in order to receive the end member 30 of the intermediate conduit 23. It is desirable that the coal be discharged from the conduit 24 in a flat sheet of uniform cross sectional area throughout, and hence, as the discharge conduit 24 extends upwardly and forwardly toward the firing opening 12, its cross sectional configuration varies as will presently appear.

From its circular rearward end, the conduit 24 expands laterally into a section as illustrated in Figure 8, having a substantially flat bottom, and arcuate sides and top, from which the cross sectional configuration of the conduit changes to that illustrated in Figure 7, having the flat bottom wall 35, the vertical sides 36, 37 and the arcuate roof 38. As the conduit 24 continues upwardly its cross sectional shape changes in a manner as illustrated by Figures 5 and 6, wherein the roof 38 is flat and the bottom wall 35 is arcuate and curves away from the normal path of the coal passing through the conduit so that frictional resistance may be reduced to a minimum.

By the particular construction of the discharge conduit 24, the fuel, as it is propelled through the conduit, passes along the flat bottom wall 35 at the lower end of the conduit and then the direction of the fuel is changed so that it passes along the flat roof 38 at the upper end of the conduit. Since the lower portion of the flat bottom wall 35 and the upper portion of the flat roof 38 are formed by arcs of relatively large circles, the velocity of the fuel in its passages through the discharge conduit is not diminished by tortuous bends and curves. Propelling the fuel along the flat walls 35 and 38 permits the fuel to be discharged in a thin, wide sheet which insures even delivery of fuel to the firebed on the grates 9.

The forwardly directed portion 25 of the discharge conduit 24 is preferably in the form of a separate casting which is secured to the discharge conduit 24 by the bolts 39 passing through lugs such as 39a. Its transverse cross sectional shape 55 conforms substantially to the upper portion of the discharge conduit as shown in Figures 5 and 6. At its upper forward end, the forwardly directed portion 25 is provided at each side with a laterally curved fuel deflecting channel such as 40 for diverting a portion of the fuel to the sides of the firebed. A plate 41 is disposed beneath the upper wall of the portion 25 and is provided with abutments such as 42 which stop the forward advance of a portion of the fuel stream and deflect 65 it to the rear corners of the firebed. Preferably, the vertical height of the forwardly directed portion 25 is slightly greater than the thickness of the fuel stream.

In the form of the invention illustrated in Figures 10 to 12 inclusive, the discharge conduit 24 and the trough 17 are connected by an intermediate conduit 45 which consists of a flexible tube 46 and a sleeve member 47 telescopically mounted on the tubular extension 21 of the 75 trough 17. A pressure fluid head 48 is secured

within the sleeve member 47 and as the conveyor screw 18 drops the coal into the sleeve member 47, the coal is propelled through the intermediate conduit 45, the discharge conduit 24 and hence, into the firebox 11. A flexible hose 49 supplies steam or compressed air to the pressure fluid head 48.

When burning coal in furnaces, and especially in locomotive fireboxes, approximately twenty per cent (20%) of the coal is unconsumed, the greater portion of this unconsumed coal being in the form of cinders. It is an object of this invention to re-introduce such unconsumed fuel particles into the stoker conduit, there to be mixed with the fuel which is being propelled toward the furnace; this is accomplished by a novel relation which is now to be described.

In locomotives, the products of combustion pass from the firebox 11 through the flues 50 and into the smokebox 51 at the front end of the locomotive. The smokebox 51 is supported on the cylinder saddle casting 52 in the customary manner and is divided into the compartments 53 and 54 by a diaphragm or wall that comprises a rear imperforate portion 55, and a foraminous portion or screen 56. The compartment 54 communicates directly with the flues 50, and the compartment 53 communicates directly with the inside stack or petticoat pipe 57 and the smoke stack 58, through which the waste gases of combustion are discharged to the atmosphere. The waste gases of combustion carry a relatively large amount of cinders and unconsumed fuel particles which pass through the flues 50 into the compartment 54. Fine particles of unconsumed fuel pass through the foraminous portion 56 while the larger particles drop from the screen onto a chute or wall 59 which extends downwardly and are deposited in the lower portion thereof. The cinders are thus deposited into a trough-like structure 60, of which there may be two, one at each side of the exhaust nozzle 61.

These solid particles of fuel are discharged from the smokebox by a pressure fluid blast issuing from the jet head 62, disposed within each trough 60. If desired, a blower fan may be utilized to generate swiftly moving currents of pre-heated air for returning the hot cinders to the fuel steam, and the same or a similar fan may be used to propel the coal into the firebox. To prevent the dissipation of the pressure fluid blast through the smokebox, a hood 63 is provided over each trough and as the cinders drop into the zone of action of the jet head 62, they are blown rearwardly through tubes such as 64 to a point adjacent the intermediate conduit 45. At this point, the tubes 64 are each provided with the return bend 65 which reverses the direction of flow of the cinders and causes them to be delivered into the intermediate conduit 45 immediately ahead of the jet head 48. Thus, the hot cinders are introduced into the path of the coal as it passes through the stoker conduits and in this manner an intimate mixture of coal and hot cinders is spread over the grates 9. This assures the positive delivery of the cinders onto the firebed and the presence of the hot cinders in the coal stream has the effect of heating the coal to a point such that its ignition in the firebox is accelerated.

From the foregoing, it will be apparent that I have produced a stoking device which is efficient in operation, consists of but a few parts and one which will realize a marked fuel saving in practice. Various changes and modifications

of my invention may be made within the scope of the following claims.

I claim:

1. In combination with a firebox having a 5 grate and a firing opening in one of its walls above said grate, a source of fuel supply, a fuel conduit extending from such source to said firing opening, said conduit including a discharge section in communication with said firing opening, pressure fluid blast emitting means in said conduit located to discharge a blast of fluid under pressure so directed as to propel the fuel through said conduit and onto the grate and means for conveying fuel from the source of supply to said pressure fluid blast emitting means, said pressure fluid blast emitting means constituting the sole means for projecting the fuel onto the grate, said discharge section having its opposite ends offset with respect to each other and opening in 10 opposed directions, the receiving end portion of said discharge section being formed as a curved elbow and the discharge end of said discharge section being formed as a curved elbow, the outer portion of the curve of each of said elbows being straight in transverse section, said elbows being so arranged that the tangent to the outer portion of the curve of said first named elbow at its forward end intersects the outer portion of the 15 curve of said second named elbow.

2. In combination with a firebox having a grate and a firing opening in one of its walls above said grate, a source of fuel supply, a fuel conduit extending from such source to said firing opening, said conduit including a discharge section in 20 communication with said firing opening, pressure fluid blast emitting means in said conduit located to discharge a blast of fluid under pressure so directed as to propel the fuel through said conduit and onto the grate and means for conveying fuel from the source of supply to said pressure fluid blast emitting means, said pressure fluid blast emitting means constituting the sole means for projecting the fuel onto the grate, said discharge section having its opposite ends offset with respect to each other and opening in 25 opposed directions, the receiving end portion of said discharge section being formed as a curved elbow and the discharge end of said discharge section being formed as a curved elbow, the outer portion of the curve of each of said elbows being straight in transverse section, said elbows being so arranged that the tangent to the outer portion of the curve of said first named elbow at its forward end intersects the outer portion of the curve of said second named elbow.

3. In combination with a firebox having a firing opening in an upright wall thereof, a source of fuel supply, a fuel conduit extending from such source to said firing opening, said conduit including a discharge section in communication with said firing opening, means for generating a fluid stream in said conduit so directed as to propel the fuel through said conduit and said firing opening into the firebox and means for introducing fuel into the path of said fluid stream, said fluid stream generating means constituting the sole means for projecting the fuel into the firebox, said discharge section having its opposite ends offset with respect to each other and opening in opposed directions, the receiving end portion of said discharge section being formed as a curved elbow and the discharge end portion of said discharge section being formed as a curved elbow, the outer portion of the curve of the elbow at the discharge end of said discharge section being straight in transverse section, said elbows being so arranged that the tangent to the outer portion of the curve of said first-named elbow at its forward end intersects the outer portion of the curve of said second-named elbow.

4. In combination with a firebox having a firing opening in an upright wall thereof, a source of fuel supply, a fuel conduit extending from such source to said firing opening, said conduit including a discharge section in communication with said firing opening, means for generating a fluid stream in said conduit so directed as to propel the fuel through said conduit and said firing opening into the firebox and means for introducing fuel into the path of said fluid stream, said fluid stream generating means constituting the sole means for projecting the fuel into the firebox, said discharge section having its opposite ends offset with respect to each other and opening in opposed directions, the receiving end portion of said discharge section being formed as a curved elbow and the discharge end portion of said discharge section being formed as a curved elbow, the outer portion of the curve of the elbow at the discharge end of said discharge section being straight in transverse section, said elbows being so arranged that the tangent to the outer portion of the curve of said first-named elbow at its forward end intersects the outer portion of the curve of said second-named elbow.

5. In combination with a firebox having a firing opening in an upright wall thereof, a source of fuel supply, a fuel conduit extending from such source to said firing opening, said conduit including a discharge section in communication with said firing opening, means for generating a fluid stream in said conduit so directed as to propel the fuel through said conduit and said firing opening into the firebox and means for introducing fuel into the path of said fluid stream, said fluid stream generating means constituting the sole means for projecting the fuel into the firebox, said discharge section having its opposite ends offset with respect to each other and opening in opposed directions, the receiving end portion of said discharge section being formed as a curved elbow and the discharge end portion of said discharge section being formed as a curved elbow, the outer portion of the curve of each of said elbows being straight in transverse section, said elbows being so arranged that the tangent to the outer portion of the curve of said first-named elbow at its forward end intersects the outer portion of the curve of said second-named elbow.

PAUL A. KETCHPEL
